UNITED STATES PATENT OFFICE.

EMIL KÄGI, OF WINTERTHUR, SWITZERLAND, ASSIGNOR TO THE FIRM SULZER FRERES
SOCIETE ANONYME, OF WINTERTHUR, SWITZERLAND.

COMPRESSOR.

Application filed September 3, 1926, Serial No. 133,321, and in Switzerland September 7, 1925.

This invention relates to compressors of the kind in which the compression is effected by means of the relative movement of the compressor casing and a displacement member disposed within it.

According to the present invention the displacement member within the casing is actuated by the centrifugal force set up by the movement of the casing which is driven by external means such as an electric motor or the like. Preferably the displacement member is in the form of a roller and the casing, without rotating about its own axis, executes a circular or oscillating movement.

In the preferred form also, the roller cooperates with a plunger adapted to reciprocate in a slot formed in the wall of the casing, this plunger serving to separate the suction chamber from the delivery chamber.

The invention may be carried out in various ways but one construction in which the compressor is shown in its application to a refrigerator is illustrated by way of example in the accompanying drawing, in which—

Figure 1 is a cross section along the line I—I of Figure 2, and

Figure 2 is a vertical cross section through the refrigerator and compressor.

In the construction shown in the drawing the apparatus comprises a driving motor *a*, a compressor *b*, a condenser *c* and an evaporator *d*. The compressor comprises a relatively flat casing *g*¹, somewhat in the shape of a hollow disc, enclosing a working chamber which is connected to the evaporator *d* through the suction pipe *e* and to the condenser *c* through the delivery pipe *f*. Within the casing *g*¹ is disposed a disc shaped displacement member in the form of a roller *g*² against which a reciprocating plunger *h* is pressed by means of a spring. By means of an extension *k* engaging with a ball bearing *i* (Figure 2) the compressor casing is eccentrically mounted on a disc or plate secured to the driving motor shaft *l*. Further, by means of another extension *n* connected to a fixed part *o* of the apparatus through a universal joint *m* the casing is arranged so that it can oscillate without being rotatable.

When the machine is set in motion the compressor casing executes a movement whereby its geometrical axis, which passes through both bearings, describes a cone having its apex lying in the universal joint. Owing to this, the compression member is influenced

by centrifugal force in such a way that it executes a rolling circular movement within the disc-shaped casing in the direction of the arrow and in conjunction with the reciprocating plunger sucks the cooling medium out of the evaporator and delivers it into the condenser, whence it is returned in a liquid state under a slight pressure to the evaporator.

Driving the displacement member by means of centrifugal force makes it possible to run the apparatus at a higher speed and with greater efficiency, while doing away with all stuffing boxes, thereby providing a compressor of simple and robust construction suitable for example, for use with household and other small refrigerating plants.

The condenser is placed within a cooling water tank *p* and the evaporator within a brine tank *q*, the latter being disposed within a cooling cabinet *r*. The whole machine is mounted in the cooling cabinet by means of supports *s* which also serve as protecting covers.

The condenser and evaporator coils are built into the cooling water tank and the brine tank respectively, and the connection with the rotary compressor is made through the flexible construction of the upper part. The condenser delivers the liquefied cooling medium to a collecting tank *x* from which it reaches the evaporator in the known manner through a valve *z* controlled by means of a float *y*.

A non-return valve *26* consisting of a horse-shoe shaped spring (Figure 1) is provided which prevents a return of the cooling medium from the condenser into the compressor. By means of the pipe *27* the plunger on its side remote from the displacement member is maintained under condenser pressure in order to assist the spring in pressing the plunger against the displacement member. The lower side wall *g*³ of the working chamber of the compressor is movably mounted in the casing *b* and by means of the spring *28* is pressed to any desired degree against the displacement member in order to guarantee a fluid tight joint. On the shaft *l* of the driving motor a counterweight *29* is provided which assists in balancing the centrifugal force of the compressor. The suction pipe *e* and the delivery pipe *f* can also be connected to the working chamber of the compressor by means of conduits formed in the plunger *h*.

The above described refrigerating machine

is only mentioned as one example of an application of the subject matter of this invention. The real novelty consists in the principle of driving compressors by means of 5 centrifugal force, whether such compressors are used with refrigerating machinery or for any other purpose whatever.

I claim:

1. A compressor comprising a shallow casing, a disk shaped displacement member disposed therein, and means for imparting an orbital movement to said casing to produce a relative movement between said member and said casing.
15. 2. A compressor comprising a casing, a free disk shaped displacement member disposed therein, and means for imparting an orbital movement without axial rotation to said casing to produce a centrifugal force, whereby 20 relative movement between said member and said casing is produced by the action of said centrifugal force upon said member.
3. A compressor comprising a casing having a circular chamber therein, a circular displacement member disposed within said chamber, and means for producing a relative movement between said member and said casing by imparting an orbital movement without axial rotation to said casing.
25. 4. A compressor comprising a casing having a shallow circular chamber therein, a disk shaped displacement member disposed in said chamber, a plunger seated in said casing and contacting with the periphery of said member, and means for producing a relative movement between said member and said casing by imparting an orbital movement to said casing.
30. 5. A compressor comprising a casing having a circular chamber therein, a circular member of smaller diameter than said chamber disposed therein and providing a peripheral clearance, a plunger seated in said casing and contacting with said member to divide 35 said peripheral clearance between said member and said casing into two portions, and means for producing a relative movement between said member and said casing to vary the volume of said separate portions by 40 imparting an orbital movement without axial rotation to said casing.
45. 6. A compressor comprising a casing having a chamber therein, a displacement member of smaller diameter than said chamber disposed therein and providing a peripheral clearance, a spring pressed plunger seated in 50 said casing and contacting with said member

to divide said peripheral clearance between said member and said casing into a compression and a suction chamber, a passage connecting said compression chamber with the spring pressed end of said plunger, and means for producing a relative movement between said member and said casing by imparting an orbital movement without axial rotation 60 to said casing.

7. A compressor comprising a casing having a chamber therein, a displacement member of smaller diameter than said chamber disposed therein and providing a peripheral clearance, a radial plunger seated in said casing and contacting with said member to divide said peripheral clearance between said member and said casing into a compression and a suction chamber, flexible delivery and 70 suction pipes connecting respectively with said compression and suction chambers, and means for producing a relative movement between said member and said casing by imparting an orbital movement without axial 75 rotation to said casing.

8. A compressor comprising a casing, a displacement member disposed therein, means eccentrically connected to said casing for imparting an orbital movement without 80 axial rotation to said casing to produce relative movement between said member and said casing, and a counterweight secured to said means to balance the reaction on said means of said eccentrically connected casing.

9. A compressor comprising a casing, a displacement member disposed in said casing and yieldably restrained against axial movement therein, and means for producing a relative radial movement between said casing and said member by imparting an orbital movement to said casing.

10. A compressor comprising a casing, a displacement member disposed in said casing and radially movable therein, a spring pressed member disposed in said casing and bearing against said displacement member to yieldably resist axial movement thereof, a universal joint socket, means connected to one end of said casing and pivoted in said socket, and means connected to the other end of said casing for producing a relative movement between said displacement member and said casing by imparting an orbital movement without axial rotation to said casing about 100 said universal joint socket as a center.

In testimony whereof I have affixed my signature.

EMIL KÄGI.
